J. H. WEISBROD,

CAST STEEL BODY BOLSTER.

APPLICATION FILED DEG. 9, 1913

1,109,606.

Patented Sept. 1, 1914.

UNITED STATES PATENT OFFICE.

JACOB H. WEISBROD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAST-STEEL BODY-BOLSTER.

1,109,606.

Specification of Letters Patent. Patented Sept. 1, 1914.

Application filed December 9, 1913. Serial No. 805,556.

To all whom it may concern:

Be it known that I, JACOB H. WEISBROD, residing at St. Louis, Missouri, and being a citizen of the United States, have invented 5 certain new and useful Improvements in Cast-Steel Body-Bolsters; of which the following is a full, clear, and exact description, such as will enable others skilled in the art to which it appertains to make and to use 10 the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is a front elevational view, showing a bolster constructed in accordance with the present invention. Fig. 2 is a plan view thereof. Fig. 3 is an enlarged fragmentary detailed elevational view. Fig. 4 is an end elevational view of the cast metal parts of the bolster comprising the present invention. Fig. 5 is a sectional view, the section being taken on line 5-5 of Fig. 2, looking in the direction indicated by the arrow. Fig. 6 is a similar view, the section being taken on line 6-6 of 30 Fig. 2, looking in the direction indicated by the arrow.

Referring to the parts, it will be noted that the major portion of the bolster, forming the subject-matter of the application, is 35 of cast metal, comprising a central filled portion 7 and wings 8-8, with a continuous bottom flange 9 extending from end to end of the bolster and with sill pockets 10 interposed between the wings 8 and the central 40 filler portion 7. Extending longitudinally of the car underframe, when the bolster is in position, and transversely of the bolster are vertical flanges 12, to which are attached the lower portions of the webs 13 of center 45 sills, which center sills will be hereinafter more specifically described. Opposite the flanges 12 and comprising a part of the flange outlining the wings 8, are other vertical flanges 14, which, with the bottom flange 50 9, outline said sill pockets, which pockets are open at the top for the insertion therein of center sills of a car underframe. Spanning the sill pockets 10 and lapping the bolster wings 8 is a top cover plate 55 15, which is secured by vertical rivets 16 to

flanges 17 of said wings; said top cover plate 15 having a thickened portion 18, which provides shoulders 19 adapted to contact with the upper inner faces of said vertical walls 14, so that when a car in which 60 the bolster is employed is lifted by means of jacks placed under the outer ends of said bolsters and the upper portion of the bolster is in compression, said shoulders 19 will be in contact with said upper inner faces of the 65 vertical walls 14, thereby relieving the rivets 16 of stresses ordinarily incident to such operation. To compensate for the increased weight due to the thickened portion 18 of the cover plate, channels 20 are formed in 70 the upper face thereof, said channels preferably extending at each side past the central filler.

In assembling the parts shown, the sills having been first provided with slots therefor, 75 the top cover plate 15 is projected through said slots 21 of the sills, said slots being preferably only sufficiently large to permit ready insertion of said top cover plate, after which the remaining portion of the bolster, including the wings 8 and central filler, is lifted to position in contact with the underside of said top cover plate, and connected thereto and to said center sills. Connected with the webs 13 of the center sills are top and bottom rolled sections 25 and 26, forming compression and tension chords for said sills, and a sill connecting cover plate 27 is secured to the outstanding flanges of said members 25. Connected with the webs of 80 the center sills intermediate the flanges 25 and 26 are stiffening angles 28 which, when the parts are assembled as shown in Fig. 1, increase the sectional area of the sills at the 85 bolster and occupy a position below the middle portion of said cover plate 15. The shoulders 19 of said cover plate depend below the normal plane of the top middle portion of the body of the bolster into the 90 pockets 10, and the cover plate 15 will be 95 supported by the wings 8 and central filler of the bolster. The bolster filler portion 7 is of less height than the body portion of the bolster wings or extensions adjacent 100 said pockets 10, hence the thickened or inset 105 depending portion of the plate 15 with its shoulders 19 rest in horizontal alinement with the inner or middle portions of the top bolster flanges 17, that is in alinement with 110 the body portions of the wings, thereby pro-

viding a mass of metal well adapted to resist compression stresses incident to jacking up the car.

What I claim is:

- 5 1. In a bolster having wing portions and having a plurality of center sill pockets comprising parallel spaced walls, a center filler casting intermediate said pockets and of less height than said wing portions, said 10 center filler casting comprising some of said walls, and a top cover plate spanning all of said walls and having a depending portion in contact with an upper face of said center filler casting and adapted to contact with the 15 vertical inner faces of some of said walls.
2. In a cast bolster, a unitary casting comprising a center filler portion, extensions or wings projecting outwardly at each side of and to a greater altitude than said portion, said bolster having sill pockets at two 20 sides of said filler portion, a top cover plate riveted to said extensions and depending shoulders formed on said cover plate adapted to contact with inner faces of some of 25 the walls of said pockets.
3. In a bolster, a center filler portion having vertical walls, center sills riveted directly to said walls and extending to a plane higher than said walls, said bolster having 30 wings extending transversely of said sills and to a plane higher than said center filler and having sill pockets intermediate said wings and center filler portion, and a top cover plate projected through the webs of 35 said center sills and connected with said wings, said plate depending below the top plane of said wings and abutting spaced walls of said pockets.
4. In a body bolster, a unitary casting 40 comprising a center filler portion having vertical walls and spaced wings extending to a plane higher than the top of said filler with sill pockets intermediate said filler portion and said wings, built up center sills 45 comprising vertical web plates and having

flanges resting in said pockets and a bolster top cover plate passed through openings in the webs of said center sills, a middle portion of said cover plate extending in alignment with body portions of said wings, and 50 said cover plate being secured directly to said wings.

5. In a body bolster, a unitary casting comprising a center filler portion having vertical walls and spaced wings with sill 55 pockets intermediate said filler portion and said wings, the wings extending to a plane higher than the filler portion, built up center sills comprising vertical web plates with bottom flanges resting in said pockets and 60 a bolster top cover plate passed through openings in the webs of said center sills, said top cover plate lapping and being secured to said wings and having a depending middle portion forming shoulders thereon 65 adapted to contact with upper inner faces of said wings in the normal plane of said wings.

6. In a body bolster, a unitary casting comprising a center filler portion having 70 vertical walls and spaced wings extending to a higher plane than said filler portion, there being sill pockets intermediate said filler portion and said wings, center sills comprising vertical web plates and flanges 75 resting in said pockets and a bolster top cover plate passed through openings in the webs of said center sills, said top cover plate having end portions lapping and being secured to said wings and having an 80 intermediate portion depending to a plane below the body portion of said plate, thereby forming shoulders to contact with some of the walls of said pockets.

In witness whereof I have hereunto set 85 my hand in the presence of two witnesses.

JACOB H. WEISBROD.

Witnesses:

OSCAR HOCHBERG,
JOHN M. ROHLFING.
